UNITED STATES PATENT OFFICE.

FREDERICK W. MATHIS, OF LYNCHBURG, VIRGINIA, ASSIGNOR TO DRAPER CORPORATION, OF HOPEDALE, MASSACHUSETTS, A CORPORATION OF MAINE.

SHUTTLE-FEELER THREAD PARTER AND CLAMP.

Application filed October 27, 1926. Serial No. 144,462.

This invention relates to shuttle feeler thread parters and clamps for parting and clamping the filling extending from the outgoing filling carrier or bobbin towards the 5 cloth selvage when replenishment of filling is effected.

It is now the ordinary practice to provide filling replenishing looms with shuttle feelers on which are mounted the parting and 10 clamping devices whereby, when the shuttle feeler is in its rearward shuttle feeling position, the parter and clamp may be actuated to part and clamp the filling and then move frontwardly to present the end of the 15 filling to the temple thread cutter. Such thread parters and clamps have sometimes been actuated to cut the filling by the frontward movement of the lay and have been opened as the shuttle feeler is moved rearwardly to shuttle feeling position. In some 20 other cases, also, it has been proposed to close the parter and clamp to perform the parting and clamping action by a train of mechanism associated with the transferrer, 25 and in such cases it has been usual to open the parter and clamp by a separate mechanism as the shuttle feeler moves to its rearward shuttle feeling position.

One of the objects of the present invention 30 is to provide a shuttle feeler thread parter and clamp which shall be controlled both as to its parting and opening movements by a train of mechanism connected to the transferrer.

In accordance with the present invention, 35 the thread parter and clamp is normally closed when the shuttle feeler is in front position and is positively opened by a train of mechanism connected to the transferrer as the shuttle feeler moves to its rearward 40 position and is then yieldingly closed by the said train of mechanism in order to part and clamp the filling.

The invention and novel combination of 45 parts will best be made clear from the following description and the accompanying drawings of one good form thereof.

In the drawings:

Fig. 1 is a sectional side elevation showing the shuttle feeler and associated parts provided with the present invention, the shuttle feeler parter and clamp having been yieldingly closed to part the filling through movement of the transferrer; and

Fig. 2 is a perspective view showing the

shuttle feeler in its frontward position with the parter and clamp closed to hold the filling for the action of the temple thread cutter.

The loom frame 1 may be of usual construction and, as common in this class of looms, it has mounted thereon the hopper stand 2 for supporting the hopper 3 in which the filling carriers 4 are supported. Mounted on the shaft 5 is the transferrer 6, the hub portion of which has extending downwardly therefrom the transferrer arm 7 to which is pivotally connected the dog 8 adapted to be engaged by a bunter 9 carried by the lay when the dog is placed in the path of the bunter by the indicator mechanism. When the bunter strikes the dog on call for replenishment of filling, the dog, and perforce, the transferrer arm 7 are moved frontwardly by the transferrer itself, as indicated by dotted lines in Fig. 1, and transfer a fresh filling carrier to the shuttle. 70

The lay 10 carries the usual shuttle box 11 at the filling replenishing side of the loom to receive the shuttle 12 from which the depleted filling carrier is ejected, and a new or fresh filling carrier is inserted on operation of the transferrer. These parts may be as usual and need no further description. 80

The shuttle feeler 13 is shown as pivotally mounted at 14 on a bracket 15 secured to the loom frame, and, in the present instance of the invention, the shuttle feeler passes through the slotted guides 16 to direct the feeler in its backward and forward movements. These parts also may be of usual construction. 85

Extending from the transverse or rock shaft 17 is the arm 18 having a rearwardly extending portion 19, and mounted on the arm 18 is the swinging arm 20 forming with the portion 19 of the arm 18 jaws between which a pin 21 on the shuttle feeler operates to effect movement of the shuttle feeler to and from shuttle feeling position. These parts may be substantially as heretofore constructed. 95

The shuttle feeler has pivotally mounted thereon the thread parter and clamp which may be of usual or any preferred construction, but, as herein shown, the movable member 22 of the parter and clamp is pivotally mounted upon the shuttle feeler at 23 and cooperates with a clamping member 24 to clamp the thread after it has been parted 110

by the movable parter. The details of the thread parter and clamp form no special part of the present invention and may be as usual or of any desired construction, the essentials being that the movable member, such as 22 of the parter and clamp, shall be provided with the forwardly extending arm to which is pivoted at 25 a rod 26 extending downwardly, said arm being utilized to effect certain movements of the parter and clamp as will presently appear.

Mounted upon the loom frame is a bearing 27 in which is mounted the rock shaft 28, one end of which extends beyond the bearing as at 29 and has secured thereon the arm 30, the rearwardly extending portion 31 of which is provided with an opening 32 into which projects a pin 33 extending from the transfferer arm 7, the effect being that upon forward movement of the dog 8 and the transfferer arm 7, as hereinbefore described, the arm 30 will be actuated in a clockwise direction (viewing Fig. 2) to turn the rock shaft 28.

Extending rearwardly from the rock shaft 28 is an arm 34 having an opening 35 through which extends the lower end of the rod 26, the upper end of which is pivoted to the movable parter and clamp. Below the opening in the arm 34 the rod 26 is provided with screw threads 36 in which is mounted the adjustable nut 37 and the locking nut 38.

The rod 36 above the opening 35 in the arm 34 is provided with a washer or sliding collar 39 on which rests one end of a spring 40, the upper end portion of which bears against a shoulder 41 on the rod, the construction being such that should the arm 34 be raised relative to the rod 26, the thread parter and clamp would be actuated yieldingly through the spring 40 to part and clamp the thread.

Rotative movement of the rock shaft 28 in a contraclockwise direction may be limited by a suitable stop, which in the present instance comprises the projection 42 secured in fixed position or formed as part of the fixed bearing 27, and upon the projection 42 the arm 34 may rest when the parts are in normal position, as indicated in Fig. 2.

Upon call for replenishment of filling, the transverse or rock shaft 17 is actuated as usual and as the shuttle feeler moves to its rearward feeling position, the arm 34 acting upon the rod 26 will effect opening movement of the thread parter and clamp, and upon actuation of the transfferer (as indicated in Fig. 1), the arm 34 will be raised, thereby acting yieldingly through the spring 40 to close the movable parter and clamp to clamp and part the thread, and as the shuttle feeler then moves forwardly to the position indicated in Fig. 2, the parter and clamp remain closed to posi-

tion the filling thread *a* for the action of the temple thread cutter, and the parter and clamp will remain closed until opened by the arm 34 positively as the shuttle feeler moves to its rearward feeling position.

What is claimed is:

1. In a filling replenishing loom, the combination of the transfferer, a rock shaft connected to and actuated by movement of the transfferer, a shuttle feeler thread parter and clamp, an arm extending from the rock shaft and connections secured to the arm and thread parter and clamp acting positively to open the parter and clamp as the shuttle feeler moves to thread parting and clamping position and acting yieldingly to close the parter and clamp to part and clamp the filling extending from the outgoing filling carrier upon transfer of filling.

2. In a filling replenishing loom, the combination of a shuttle feeler thread parter and clamp, the transfferer, a rock shaft actuated by the transfferer movement, an arm extending from the rock shaft, a rod connected to the thread parter and clamp and extending through said arm, a stop on the rod below the arm to cause said arm to positively open the parter and clamp as they move to thread parting position, and a spring actuated by said arm when the latter is moved by the transfferer to yieldingly operate the parter and clamp to part and clamp the filling.

3. In a filling replenishing loom, the combination of a shuttle feeler thread parter and clamp, a transfferer, a rock shaft connected to the transfferer for rocking movement by the transfferer movement, an arm extending from the rock shaft and having an opening therethrough, a rod connected to the thread parter and clamp and extending through the opening in the arm, a stop on the rod below the opening to cause positive opening of the parter and clamp as the parter and clamp move to parting and clamping position, and a spring on the rod above the arm for yieldingly closing the parter and clamp when the transfferer replenishes the filling.

4. In a filling replenishing loom, the combination of a shuttle feeler thread parter, a transfferer for replenishing the filling, a rock shaft operatively connected to the transfferer, an arm extending from the rock shaft, and uninterrupted connections extending between the arm and thread parter and secured to each for both opening and closing the parter.

5. In a filling replenishing loom, the combination of a shuttle feeler thread parter, a transfferer for replenishing the filling, a rock shaft operatively connected to the transfferer, an arm extending from the rock shaft, and connections between the arm and

thread parter including a rod and a spring for both opening and closing the parter.

6. In a filling replenishing loom, the combination of a shuttle feeler, a thread parter and clamp mounted on the shuttle feeler, a rock shaft having an arm connected to the downwardly extending transerrer arm and a rearwardly extending arm having an opening, a rod connected to the thread

parter and clamp and extending through 10 said opening, an adjustable nut on the rod below the opening, and a spring on the rod above the opening to yieldingly close the parter and clamp.

In testimony whereof, I have signed my 15 name to this specification.

FREDERICK W. MATHIS.
